CLAIM

The ornamental design for a scanning device cover, as shown and described.

DESCRIPTION

FIG. 1 is an upper, front, right perspective view of a scanning device cover of our new design;

FIG. 2 is a front view thereof;

FIG. 3 is a rear view thereof;

FIG. 4 is a right view thereof;

FIG. 5 is a left view thereof;

FIG. 6 is a top view thereof; and,

FIG. 7 is a bottom view thereof.

Broken lines formed by equal length dashes (i.e., dash-dash lines) represent unclaimed subject matter and form no part of the claimed design.

1 Claim, 2 Drawing Sheets
